POWER SWEEPER

Floyd Drumm, Lansing, Mich., assignor to Ideal Power Lawn Mower Company, Lansing, Mich., a corporation of Michigan

Application June 27, 1938, Serial No. 215,989

7 Claims. (Cl. 15—83)

This invention relates to power driven sweeping machines, and more particularly to sweeping machines embodying rotary brushes and refuse collecting hoppers.

This invention is an improvement on that disclosed in my prior co-pending application Serial No. 126,350, filed February 18, 1937.

In a power sweeping machine of the type to which this invention relates, it is necessary to support the rotary brush and hopper in the proper relationship to the surface to be swept. Where the surface to be swept is perfectly flat the solution of this problem is relatively simple. On the other hand, where such surface is uneven, particularly in the case of floors having different levels connected by ramps, the problem becomes more difficult as it is not only necessary that the brush and hopper be maintained in the proper relation to the floor, but also that they be held in proper relationship to each other. Furthermore, some provision must be made for adjustment of the supports to compensate for brush wear.

My invention overcomes the aforementioned difficulties by novel means for connecting the brush and hopper together and to the traction frame. Broadly the invention comprises an articulated power sweeper consisting of a brush carrying frame pivotally attached at the back to a main or traction frame, and at the front pivotally attached to a refuse collecting hopper. The pivotal connections are on horizontal axes whereby the three parts may swing vertically with respect to each other. The invention also includes a novel form of pivotal connection between the brush carrying frame and hopper, and a novel ground engaging support for the brush carrying frame, both of which are adjustable to allow the brush to be lowered as it wears, but provides for maintenance of the proper relationship between the hopper and the brush.

In the drawing:

Figure 1 is a perspective view of a complete power operated sweeping machine embodying my invention;

Figure 2 is a cross-sectional view of a portion of the structure shown in Figure 1 taken on substantially the line 2—2 thereof;

Figure 3 is a fragmentary plan view of a portion of the mechanism shown in Figure 1;

Figure 4 is a diagrammatic view showing the manner in which the three units of the device may move relative to each other; and

Figure 5 is a fragmentary cross-sectional view taken on substantially the line 5—5 of Figure 3.

In general, the sweeper comprises a traction unit 10, a rotary brush unit 11 pivotally connected thereto, and a hopper 12 pivotally connected to the brush unit 11, both pivots being located on horizontal axes transverse of the structure.

The traction unit comprises a traction frame 13 supported at its forward end on a pair of traction wheels 14 and at its rear end on a caster wheel 15. Mounted on the frame 13 is a suitable power plant 16, which in this instance is an internal combustion engine. The drive shaft of the power plant is connected by any suitable means to the traction wheels 14 in order to furnish motive power thereto. A pair of upwardly and rearwardly extending arms 18 to which handles 19 are connected provide a means for guiding the sweeper.

Mounted on the forward end of the frame 13 is a transverse shaft 20 which carries a pair of arms 21 having pivotal movement about the axis thereof. These arms 21 are fixed to a brush carrying frame 22. The brush carrying frame has depending side walls 23 on which are mounted bearings 24. A brush 25 is mounted on a transverse shaft which is rotatable in the bearings 24. One end of the shaft carries a sprocket, not shown, which is connected by a drive chain 17 to the drive shaft of the power plant 16 whereby the brush may be rotated.

An upstanding arm 26 is mounted on the shaft 23 and its upper end is connected by a rod 27 to a bell crank 28 mounted on a cross bar 30 secured to the arms 18. A chain 31 is also connected at one end to the upper end of the arm 26, and at its other end the chain is connected to the top of the brush carrying frame 22. With the arrangement just described it is possible to lift the brush from the floor by applying a downward force to a handle 29 in the bell crank 28 which is applied through the bell crank 28 and link 27 and chain 31 to the brush frame.

The foregoing structure is all more fully described in my aforesaid co-pending application.

Rigidly secured to the forward ends of the side walls 23 of the brush carrying frame are a pair of supporting blocks 32, one at each side of said frame. The outer faces of the blocks 32 are serrated. These faces engage serrated faces of a pair of complementary supporting blocks 33. In the outer face of each block 33 is a channel shaped groove and slidable in this groove is a bar 34. The bar 34 has an elongated slot 35 therein. A bolt 36, with a nut 36a thereon, extends through the slot 35 and through centrally

located apertures in the blocks 32 and 33 whereby the three last mentioned parts may be rigidly clamped together. It will be readily apparent that the bar 34 may be adjusted vertically with respect to the frame 23 by merely loosening the nut 36 sufficiently to allow the bar to slide. The bar 34 may be rotatably adjusted about the bolt 36 and held in any position by the opposing teeth on the blocks 32 and 33. It may, of course, be clamped in any position in which it is set.

The bar 34 carries an extension 37 integral herewith, which forms a bearing bracket for a caster wheel 38. The caster wheel 38 has a shaft 39 which extends upwardly through the bearing bracket, and preferably anti-friction bearings 40 are employed between the caster wheel and the bearing bracket. From the foregoing it will be readily apparent that the relative height of the brush 25 may be varied at will by merely adjusting the position of the bar 34. In this manner, as the brush becomes worn, it can be lowered so that it will always make the proper contact with the floor.

Near the upper front corner of the side walls 23 of the brush carrying frame is another pair of supporting blocks 41 and 42 similar to the blocks 32 and 33 previously described. The inner blocks 42 are rigidly secured to side walls 23, and the adjacent faces of the blocks are serrated. The outer block 41 has a horizontally extending channel-shaped groove in which a supporting bar 43 is slidably mounted. This supporting bar 43 has an elongated slot 44 through which a bolt 45 provided with a nut 46 passes. It will be readily seen that the bar 43 may be adjusted longitudinally as well as rotatably with respect to the brush frame by loosening the nut 46 and moving the block 41 or sliding the bar 43 in the same manner as the bar 34 previously described.

The side walls 12a of the hopper 12 are provided at their upper edges with inwardly extending flanges 12b. Mounted on the flanges 12b are a pair of brackets 43. The brackets 43 have upstanding face portions 48a in which are arcuate slots 49. The forwardly extending portions of the brackets 43 are slotted at 53. These brackets 48 are secured to the flanges 12b by means of handles 54 from which extend threaded shafts 55. The shafts 55 pass through holes in the flanges 12b and are threaded into bosses secured to the under side of the flanges 12b. When the handles 54 are screwed tightly against the brackets 48 the hopper is securely attached thereto, but the latter may be easily removed by merely loosening the handles, whereupon the hopper may be slipped from the brackets as shafts 55 slide out of the slots 53.

Extending outwardly from the upstanding face portion 48a of each bracket 48 is an integral boss 50 which is provided with an axial bore 50b. Each arm 43 is also provided with an integral boss 47 which extends laterally thereof toward the bracket 48. Extending axially through the boss 47 is a threaded bore 47a. The arm 43 is also bored at 50a and this bore is also threaded. A cap screw 52 extends through the bore 50b in the bracket 48 and is secured in the bore 50a in the arm 43. A cap screw 51 extends through the slot 49 in the bracket 48 and is threaded into the bore 47a in the arm 43. The cap screw 52 forms the pivot about which the bracket 48 and the attached hopper may rotate, while the cap screw 51 provides a stop to limit the relative movement of the bracket 48 and the arm 43.

The cap screw 51 may be drawn up tightly to clamp the bracket 48 to the arm 43 if it is desired to hold them rigidly together.

With the pivotal connection just described it is possible to dump the hopper without removing it from the brackets 48. It is merely necessary to lift the front end of the hopper, thereby tilting the hopper about pivots 52. The brush 25 may then be lifted over the pile of refuse by operating the handle 29 in the proper manner.

It is also possible to tilt the hopper about pivots 52 to a position above the brush carrying frame, where it rests against the brush carrying frame. The sweeper and hopper may then be raised simultaneously from the floor by means of the handle 29 in order to transport the sweeper from one place to another, without the friction of the casters and brush on the floor.

At the forward end of the hopper 12 a reinforcing channel bar 56 is attached, to which a pair of bearing brackets 57 are rigidly secured. Caster wheels 58 having vertical pivot shafts 59 are mounted in bearings in these bearing blocks. From the foregoing it will be apparent that the hopper is supported at its front end by the casters 58 and at its rear end by the pivots on the brackets 48 and the bars 43.

Referring now more particularly to Figure 4, it will be seen that the articulated connections of the traction frame, the brush frame and the hopper are such as to allow a considerable amount of relative movement of the three units 10, 11 and 12. The supporting casters 38 and 58 hold the brush and the hopper respectively in the proper relationship to the surface which is being swept, while the two pivotal connections allow the brush and hopper to follow an irregular surface such as the three separate inclines shown in Figure 4. Inasmuch as hopper is pivoted to the brush frame there will be little displacement of the hopper relative to the brush, as the brush passes over the irregularities of the floor. Consequently, the hopper will always be in a position to receive the refuse to be swept into it by the rotating brush.

It will be evident that as the brush wears the brush carrying frame 22 must be lowered with respect to the hopper 12. It is also necessary to move the hopper toward the brush. Thus when the brush has been reduced in diameter to a degree such that it does not properly contact the floor, the bar 34 may be adjusted vertically relative to the block 33, the bar 43 may be adjusted horizontally relative to block 41, and the block 41 may be rotated about bolt 45. In this manner the floor, brush and hopper may again be brought into proper relationship.

The scope of the invention is indicated by the appended claims.

I claim:

1. In a power sweeper, a traction frame supported on wheels, a brush carrying frame pivotally connected adjacent its rear end to the traction frame, a brush rotatably mounted on the brush carrying frame, ground engaging supports adjustably connected to the brush carrying frame adjacent the front end thereof for regulating the position of the brush relative to the ground, a hopper located forwardly of the brush carrying frame, said hopper having an open side in close proximity to the rotatable brush, and adjustable pivot means connecting the hopper to the brush carrying frame for vertical oscillation relative thereto, said means being adjustable both

vertically and horizontally relative to the brush carrying frame.

2. An articulated power sweeper comprising a main frame supported on wheels, a hopper spaced longitudinally from said main frame, a brush carrying frame between said main frame and said hopper, a rotatable brush mounted on said brush carrying frame, said brush carrying frame being pivotally connected to the main frame on an axis extending transversely of said frame and located adjacent one side of said brush carrying frame, means pivotally connecting the brush carrying frame to the hopper on an axis extending transversely of said frames and located adjacent the opposite side of the brush carrying frame, ground engaging supports mounted on the side of the hopper remote from the brush carrying frame, and ground engaging supports mounted on the side of the brush carrying frame adjacent the hopper.

3. In a power sweeper, a traction frame supported on wheels, a brush carrying frame pivotally connected adjacent its rear end to the traction frame, a brush rotatably mounted on the brush carrying frame, a hopper located forwardly of the brush carrying frame, said hopper having an open side in close proximity to the rotatable brush, and adjustable pivot means connecting the hopper to the brush carrying frame for vertical oscillation relative thereto, said means being adjustable both vertically and horizontally relative to the brush carrying frame.

4. An articulated power sweeper comprising a main frame supported on wheels, a hopper spaced longitudinally from said main frame, a brush carrying frame between said main frame and said hopper, a rotatable brush mounted on said brush carrying frame, said brush carrying frame being pivotally connected to the main frame on an axis extending transversely of said frames and located adjacent one side of said brush carrying frame, means pivotally connecting the brush carrying frame to the hopper on an axis extending transversely of said frames and located adjacent the opposite side of the brush carrying frame, said means comprising an arm slidably connected at one end to the brush carrying frame and pivotally connected adjacent the other end to the hopper whereby the position of the hopper with respect to the brush may be varied.

5. An articulated power sweeper comprising a main frame supported on wheels, a hopper spaced longitudinally from said main frame, a brush carrying frame between said main frame and said

hopper, a rotatable brush mounted on said brush carrying frame, said brush carrying frame being pivotally connected to the main frame on an axis extending transversely of said frames and located adjacent one side of said brush carrying frame, means pivotally connecting the brush carrying frame to the hopper on an axis extending transversely of said frames and located adjacent the opposite side of the brush carrying frame, said means comprising an arm pivotally connected at one end to the brush carrying frame and pivotally connected adjacent the other end to the hopper whereby the position of the hopper with respect to the brush may be varied.

6. An articulated power sweeper comprising a main frame supported on wheels, a hopper spaced longitudinally from said main frame, a brush carrying frame between said main frame and said hopper, a rotatable brush mounted on said brush carrying frame, said brush carrying frame being pivotally connected to the main frame on an axis extending transversely of said frames and located adjacent one side of said brush carrying frame, means pivotally connecting the brush carrying frame to the hopper on an axis extending transversely of said frames and located adjacent the opposite side of the brush carrying frame, said means comprising an arm slidably and pivotally connected at one end to the brush carrying frame and pivotally connected adjacent the other end to the hopper whereby the position of the hopper with respect to the brush may be varied.

7. An articulated power sweeper comprising a main frame supported on wheels, a hopper spaced longitudinally from said main frame, a brush carrying frame between said main frame and said hopper, a rotatable brush mounted on said brush carrying frame, said brush carrying frame being pivotally connected to the main frame on an axis extending transversely of said frame and located adjacent one side of said brush carrying frame, means pivotally connecting the brush carrying frame to the hopper on an axis extending transversely of said frames and located adjacent the opposite side of the brush carrying frame, a ground engaging support mounted on the hopper remote from the pivotal connection between the hopper and the brush carrying frame, and a ground engaging support mounted on the brush carrying frame remote from the pivotal connection between the brush carrying frame and the main frame.

FLOYD DRUMM.
